Application May 24, 1957, Serial No. 46,344

Term of patent 14 years

(Cl. D41—1)

FIG. 1.

FIG. 2.

Fig. 1 is a view in perspective of a hook embodying our new design as viewed from the front and right side;

Fig. 2 is a view in front elevation;

Fig. 3 is a view in left side elevation;

Fig. 4 is a view in rear elevation; and

Fig. 5 is a horizontal cross-sectional view thereof taken on line 5—5 of Fig. 3.

The dominant features of our design reside in those portions of the hook shown in full lines.

We claim:

The ornamental design for a hook, as shown and described.
